Victor Beroud,

INVENTOR.

Geo. H. Kimmel.

ATTORNEY.

UNITED STATES PATENT OFFICE.

VICTOR BEROUD, OF PELICAN RAPIDS, MINNESOTA.

GRAVE MARKER.

1,425,361.

Specification of Letters Patent. Patented Aug. 8, 1922.

Application filed August 11, 1921. Serial No. 491,549.

To all whom it may concern:

Be it known that I, VICTOR BEROUD, a citizen of the United States, residing at Pelican Rapids, in the county of Otter Tail 5 and State of Minnesota, have invented certain new and useful Improvements in Grave Markers, of which the following is a specification.

This invention relates to certain new and 10 useful improvements in markers for graves, land marks and the like, and the primary object of the invention is to produce a light, attractive and neatly appearing device adapted for use as a marker of general 15 utility.

One of the objects of the invention is to provide a grave marker of novel design for receiving a photograph and glass protecting plate to designate a certain plot of ground, 20 including a hingedly connected protecting cover therefor permitting the same to be raised so that the photograph or epitaph may be observed.

The invention will be best understood 25 from a consideration of the following detailed description taken in connection with the accompanying drawing forming a part of this specification, with the understanding, however, that the invention is not confined 30 to any strict conformity with the showing in the drawing, but may be changed and modified so long as such changes and modifications mark no material departure from the salient features of the invention as expressed in the appended claims.

I attain these objects and others in the accompanying drawing, wherein:

Figure 1 is a longitudinal sectional view 40 through the marker.

Fig. 2 is a sectional view taken on the line 2-2 of Fig. 1.

Fig. 3 is a detail view showing the frame and a descriptive photograph therefor, adapted to be carried by the marker.

Fig. 4 is a perspective view of the photograph frame; and

Fig. 5 is an end view of the device.

Referring now to the drawings wherein like parts designate corresponding parts 50 throughout the several views, 5 designates the front wall, 6 the rear wall and 7, 8, the sides of a substantially rectangular casing or frame, which may be constructed of metal, enamel, or other material, said casing having a sloping top 9 extending from the rear

to the front wall, as clearly shown by Fig. 1 of the drawing. The casing has attached thereto a pair of front and rear standards or supports 10, 11, rigidly secured to the inner walls of the front and rear of said casing, 60 said standards or supports being pointed at their lower ends 12 for easy penetration into the earth, whereby the marker may be easily and conveniently positioned where so desired.

An open frame designated in its entirety by numeral 13 is provided with side flanges 14 and with transverse apertures 15 at their rear, whereby the said frame may be pivoted to the side walls 7, 8, of the casing. The said 70 frame above referred to is designed to receive a photograph 16 or an epitaph or inscription thereon and in addition the protecting glass plate 17, as is well understood.

An outer covering or casing of the same 75 configuration as the inner casing above referred to has its rear wall 18 provided with slots 19 to permit the top cover 20 to be raised, and held in such position by the brackets 21.

By reason of the construction it will be readily seen that I have provided a novel and improved grave marker, which may possess all the neatness and attractiveness 80 of a tablet or memorial slab and one which will withstand the inclemency of the weather for many years without particular care or attention. The device lends itself to be constructed of as expensive or as cheap material as occasion may require, and otherwise constitutes a very satisfactory substitute for expensive and very heavy marble, granite or stone tomb-stones.

In the accompanying drawings, I have 85 illustrated my invention embodied in one form by way of example, and which in practice has been found to be highly satisfactory in obtaining the desired results. It will be obvious however that other embodiments 90 may be adopted, and that various changes 100 in the details of construction may be resorted to by those skilled in the art without departing from the spirit and scope of the invention. It is furthermore understood that the invention is not necessarily limited or restricted to the precise elements shown except in so far as such limitations are specified in the subject matter being claimed.

What I claim is:

1. A marker of the class described com- 110

- prising an inner casing, supporting standards attached to said casing, a frame superposed on the top of said casing and an outer protecting cover for said casing and frame.
- 5 2. A marker of the class described comprising an inner casing having a sloping top, supporting standards secured to the front and rear walls of the casing, an open frame superposed on the top of the said casing and 10 an outer protecting cover disposed over the said inner casing and frame.
3. A marker of the class described comprising an inner casing having a sloping top, supporting standards secured to the inner 15 front and rear walls of the casing, an open frame pivotally connected to the rear of the said casing and disposed on the top

thereof, and an outer protecting cover overlying the casing and the frame.

4. A marker of the class described comprising an inner, substantially rectangular casing having a sloping top, supporting standards secured to the inner front and rear walls of the casing adapted for penetration in the earth, an open frame pivotally connected to the side walls and near the top of the said inner casing, a substantially rectangular outer protecting cover also pivotally connected to the sides of the inner casing and means for maintaining said outer protecting cover in its raised position.

In testimony whereof, I affix my signature hereto.

VICTOR BEROUUD.
